PUMP FOR LIFTING HOT LIQUID

Royce E. Boggs, Lakeside, Calif., assignor to Rohr Aircraft Corporation, Chula Vista, Calif., a corporation of California

Application October 1, 1956, Serial No. 613,146

6 Claims. (Cl. 103—178)

In the manufacture of steel and stainless steel articles, they are often heat treated by immersing them in hot molten salt baths for periods of 20 minutes or longer. While they are immersed small amounts of scale and slag are formed which get into the salt bath and contaminate it. Upon immersing one batch of articles after another, the amount of scale and slag in the bath progressively increases and contaminates it to such an extent as to render it inefficient for its intended purpose. It has been found that the unwanted oxides or other compounds formed in the bath are somewhat heavier than the salt composing the bath and settle in the bottom of the bath as a sludge. It is a main purpose of my invention to provide a pump capable of removing this sludge or a major portion thereof from the bottom of the salt bath even when the bath has a temperature of about 1600° F.

Another object is to provide a pump made entirely of metal which is capable of withstanding the high temperature of the bath repeatedly without impairment of its pumping ability.

A further object is to provide a pump composed of a small number of moving parts and which is simple in construction and easy to operate.

Another object is to provide means at the bottom of the pump for permitting the hot salt therein to drain out after the pump has been used and is being raised out of the salt bath.

Further objects will become apparent as the description of my novel pump proceeds. For a better understanding of the invention, reference is made to the accompanying drawings, in which:

Fig. 1 is a view of the pump in operative position in a salt bath also showing some equipment used with the pump, partly in section;

Fig. 2 is a front view, partly in section, showing the outer portion of the pump;

Fig. 3 is a bottom view of the pump portion of Fig. 2;

Fig. 4 is a front view of the pump piston rod and piston; and

Fig. 5 is a sectional view taken on line 5—5 of Fig. 4.

As shown in Fig. 1 the pump 10 is in position for pumping out sludge at the bottom of a salt bath 11 maintained at a temperature of 1600° F. in a deep container or tank 12 by suitable heating means (not shown). The salt bath is used for heat treating steel or stainless steel articles (not shown) lowered into the bath and allowed to soak therein. A pair of doors 13 having rollers 14 which roll along a pair of channel beams 15 may be moved into the position shown to hold the pump upright in bath 11. The pump comprises a long cylindrical metal tube 16 to which a surrounding supporting bracket 17 is secured, the bracket 17 resting on doors 13 to steady the pump. A metal sleeve 18 (see Fig. 2) has a loose sliding fit along the lower end of tube 16, the sleeve having two or more vertical slots 19 extending therethrough. A collar 20 surrounds and is welded to tube 16, the collar having a plurality of depending fingers 21 whose lower

2

ends 22 are bent in to enter the slots 19. While the two slots 19 are shown as being spaced 90 degrees apart for clarity, it will be understood that they may be spaced 180 degrees apart and also that more than two slots may be provided if desired. The fingers 21 thus prevent the sleeve 18 from sliding off tube 16 when the pump is raised out of bath 11. If desired a reinforcing ring 23 may surround the fingers 21 above their lower ends and be welded thereto.

10 A check valve 24 is secured to sleeve 18 above the lower end thereof, this valve comprising a metal ring 25 secured in position by four pins 26 passing through sleeve 18. A floating disc 27 of a diameter substantially greater than the inside diameter of ring 25 is adapted to rest on the top of ring 25 to close the valve or to move into the position shown in Fig. 2 to permit liquid to flow up through the valve. Three or more small pins 28 extending through sleeve 18 limit the upward movement of disc 27 away from its valve seat. The horizontal bottom face 29 of sleeve 18 has a plurality of notches 30 cut therein, these notches providing passageways for liquid entering the bottom of the pump when the face 29 of sleeve 18 is resting on the floor 31 of tank 12, as shown in Fig. 1. In this pumping position, tube 16 has been lowered from its position shown in Fig. 2, the ends 22 of fingers 21 are at the bottom of slots 19 and the bottom end 32 of tube 16 is at a level below the bottom of slots 19 so that when the piston to be described is operated, no fluid can enter the pump through any of the slots 19. 15 In this position collar 20 is in contact with the top of sleeve 18, so that the weight of tube 16 is carried by sleeve 18 and the floor 31 of the tank.

The liquid is raised by a piston 33 having a cylindrical hole 34 therethrough, the top portion 35 of the piston 35 being cylindrical and having sliding contact with the interior face of tube 16. The bottom portion 36 of the piston is frusto-conical in shape to facilitate its downward movement through the liquid in tube 16. A floating metal disc 37 is adapted to seat on top of piston 33 to block the passage of liquid downward through hole 34. The piston is attached to the bottom of a long solid piston rod 38 by three cylindrical bars 39 whose upper ends are welded to rod 38 and whose lower portions 40 are parallel and are welded to the top of piston 33. 20 Disc 37 has a loose sliding fit with the portions 40 of bars 39 which keep the disc centered over hole 34 and the bottom end 41 of rod 38 serves as a stop to limit the upward movement of disc 37. The top of rod 38 terminates in a ring 42 which has attached a collar 43 whose upper portion is of larger diameter than tube 16 and rests on top of tube 16 to support piston rod 38 and piston 33. The lower portion 44 of collar 43 is cylindrical and fits in the top of tube 16 to center rod 38 therein while the pump is being put in tank 12. If desired, two 25 or more holes 45 may be drilled through collar 43 to permit the exit of air from tube 16 as the pump is lowered into salt bath 11. All the parts of the pump as above described are preferably made of stainless steel to minimize oxidation and deterioration at the high temperatures 30 at which the pump is used.

Attached to and surrounding the top of tube 16 is a metal box 46 whose bottom 47 is at a level below the top of tube 16, the box having a downwardly inclined chute 48 constructed to direct the liquid pumped into a can 49.

To operate the pump, a reversible power driven winch 50 is provided, the winch having a flexible cable 51 to which a hook 52 fitting in ring 42 is attached. When the pump is put in position, as shown in Fig. 1, with the grooves 30 submerged in the sludge at the bottom of salt bath 11, the winch is operated to raise piston rod 38 and piston 33. As the piston is raised, the liquid above it

is forced out of the top of pipe 16, falls into box 46 and flows into can 49. As the piston 33 is rising, some of the sludge on the bottom 31 of the tank passes through notches 30, and up through the opening in ring 25 causing the disc 27 to rise off its seat. The sludge continues to rise in pipe 16 as piston 33 rises and with piston 15 having a stroke of 15 feet or more, pipe 16 contains a substantial volume of sludge when the piston has reached the top of its stroke. The winch 50 is now reversed and the rod 38 descends under the action of gravity. As piston 33 descends, disc 37 raises from its seat permitting the piston and rod 38 to descend through the liquid sludge in pipe 16. The pressure of the sludge in the pipe causes disc 27 to move down onto its seat and prevent the escape of sludge from the bottom of the pipe. When the piston is at substantially the bottom of tube 16, winch 50 is reversed to raise the piston and on its upstroke the liquid sludge in tube 16 is discharged out of its top and is conveyed into can 49. On the upstroke of the piston, more sludge along the bottom of the tank is drawn into notches 30, raises disc 27 and flows up into tube 16. By repeated strokes of the piston the layer of hot sludge which may be an inch or more deep on the bottom of tank 12 may be removed so that it cannot gradually chemically unite with the salt in the bath and contaminate it.

When the pumping is completed, the piston rod 38 and piston 33 are raised out of tube 16 and tube 16 is raised out of salt bath 11. As the tube is raised, its lower end slides up in sleeve 18 until it is in the position shown in Fig. 2 whereupon the sleeve and tube rise together. The slots 19 are open and the column of hot salt contained in tube 16 drains out through these slots into bath 11. If this salt were allowed to remain in the tube, it would solidify as the tube cooled to normal room temperature and be difficult to remove later.

This invention may be embodied in other forms or carried out in other ways without departing from the spirit or essential characteristics thereof. The present embodiment of the invention is therefore to be considered as in all respects illustrative and not restrictive, the scope of the invention being indicated by the appended claims, and all changes which come within the meaning and range of equivalency of the claims are intended to be embraced therein.

Having thus described my invention, what I claim as new and useful and desire to secure by Letters Patent is:

1. A pump adapted to lift hot liquid comprising, in combination: a long substantially vertical metal tube; a metal sleeve engaging the peripheral wall of said tube and slidable along the lower end thereof; means cooperating with said tube and sleeve to prevent said sleeve from falling off the end of said tube; a hollow metal valve seat secured to the lower end of said sleeve; a metal check valve adapted to rest on said valve seat, the lower end of said sleeve being provided with a plurality of openings terminating in its lower end face to admit liquid to said valve seat; a long metal rod extending into and movable in said tube, the lower end of said rod being provided with a metal piston slidable along the inner wall of said tube and the top of said rod extending beyond the top of said tube.

2. A pump as claimed in claim 1, in which said metal piston has a vertical hole through the center thereof; and a metal plate supported for free vertical movement over said piston and adapted upon the upstroke of said piston to rest on the top thereof and prevent the passage of liquid through said vertical hole.

3. A pump as claimed in claim 2, in which the plurality of spaced apart metal bars have their upper ends welded to the lower end of said rod and their bottom ends welded to the top of said piston, said bars being in sliding contact with the periphery of said plate and adapted to prevent sidewise movement thereof.

4. A pump adapted to lift hot liquid from a region near the bottom of a tank comprising, in combination: a long substantially vertical metal tube, a metal sleeve engaging the peripheral wall of said tube and slidable along the lower end thereof, said sleeve having a plurality of spaced apart elongated vertical slots extending therethrough; a plurality of fingers having their upper ends connected to said tube and their lower ends extending into said slots, the lower end of said tube closing the passageways through said slots in response to the downward movement of said tube in said sleeve; a metal ring secured within the lower end of said sleeve; a metal disc disposed on said ring and having a diameter substantially greater than the inside diameter of said ring, said disc moving up from said ring in response to the movement of liquid upward through said ring; means extending inward from said sleeve above said disc to limit the upward movement of said disc, said sleeve below said ring being provided with a plurality of openings terminating in its lower end face to admit liquid into said sleeve when its lower end face is resting on the bottom of the tank; a long metal piston rod extending into said tube and having its upper end disposed above the top of said tube; and a metal piston attached to the bottom of said rod and slidable along the inner wall of said tube.

5. A pump as claimed in claim 4, in which the means for limiting the upward movement of said disc consists of a plurality of spaced apart metal pins extending through said sleeve and disposed in a horizontal plane.

6. A pump adapted to lift hot liquid from the bottom of a tank, comprising: a long substantially vertical metal tube having its top disposed above the top of the tank; a metal sleeve in engagement with and slidable along the peripheral wall of said tube at the lower end thereof, the upper portion of said sleeve having a plurality of spaced apart slots extending therethrough, the passages through said slots being closed in response to the lowering of said sleeve and tube and the advancement of the bottom of said sleeve against the bottom of the tank; a metal check valve in the lower end of said sleeve constructed to prevent the passage of liquid downwardly therethrough; a long metal piston rod disposed in said tube and projecting from the upper end thereof; and a metal piston attached to the lower end of said piston rod and having sliding contact with the inner wall of said tube.
